Albert Becker

UNITED STATES PATENT OFFICE.

DAVID JOHN SCOTT, OF PLAINFIELD, NEW JERSEY, ASSIGNOR TO ISABELLA SCOTT AND DAVID J. SCOTT, EXECUTORS OF WALTER SCOTT, DECEASED.

MULTICOLOR OFFSET-PRESS.

1,313,123.

Specification of Letters Patent. Patented Aug. 12, 1919.

Application filed September 29, 1916. Serial No. 122,840.

To all whom it may concern:

Be it known that I, DAVID J. SCOTT, a citizen of the United States, and a resident of Plainfield, in the county of Union and State of New Jersey, have invented certain new and useful Improvements in Multicolor Offset-Presses, of which the following is a specification.

The present invention relates generally to 10 a multi-color offset press and has more particularly reference to the arrangement of the printing and other units in such a press.

The main object of the invention is the production of a machine that will print in 15 several colors, and preferably on both sides of the paper, by the offset method without the omission of any elements necessary to produce high grade results, and in which the parts are so arranged that they may be 20 easily accessible for the purpose of manipulation by the operator.

Accordingly, the invention consists of the features of construction, combination of parts and arrangement of elements, several 25 preferred forms of which are disclosed in the accompanying drawings. However, changes of construction may be made in the particular construction herein disclosed without departing from the legitimate and intended 30 scope of the invention.

The drawing is a diagrammatic view in elevation showing the paper printed in two colors on one side and in four colors on the other side.

35 The machine is built up of a number of units, each of which comprises a form-carrying member 1, a transfer or blanket member 2 and an impression member 3, the form-carrying and transfer members being 40 arranged one above the other and the impression member out of line with the other members to form an exposed operating side. In addition, suitable inking mechanism, indicated by O, and, when the work requires 45 it, dampening mechanism, indicated by N, are used. It will be understood that suitable means are provided for throwing off the impression or for separating the cylinders as indicated by the movable bearings in 50 which the blanket and impression cylinders are mounted, and that also the dampening mechanism is movable by means of handle 34 in and out of engagement with the form-

carrying member as indicated diagrammatically. Furthermore, when anti-smutting device 37 is used in connection with certain of the impression cylinders, as will be more fully hereinafter described, such devices are likewise movable with relation to said impression cylinders as by means of a handle 60 35.

In the exemplification of the machine here shown, there are two groups of units indicated by U and U'. One group consists of a set of two units A' A' superposed one 65 above the other with their operating sides facing in the same direction. The other group U' consists of two sets of units, one of which B' C' consists of two units arranged one above the other with their operating 70 sides facing the same way; and the other set consists of two units B C in superposed relation with their operating sides facing the same way, the two sets comprising group U' being arranged back to back as shown and 75 the two groups U U' being spaced apart to provide an intervening passageway as shown. In this instance, the units in the set constituting group U print on one side of the paper while the units in the two sets 80 constituting the group U' print on the other side of the paper. It will be noted that in connection with each impression cylinder of the units of the sets in group U' there is associated an anti-smutting device 37. The 85 source of supply of paper I is in spaced relation to the group U to afford a gangway and suitable guides are provided for leading the web to the machine. In like manner, the folding mechanism L is arranged to afford 90 unobstructed access to the group U', there being a gangway between the group U' and the folder.

The web is led from the source of supply I to the impression cylinder of the lowermost unit A' of group U, thence to the impression cylinder of the uppermost unit A', thence over the machine to the impression cylinder of the unit B', thence to the impression cylinder of the unit C', thence to 95 the impression cylinder of unit C and thence to the impression cylinder of unit B. With the former folder shown in connection with this device, the web may then pass to the slitter 104 where the web is severed and one 100 half of it doubled back on the other half by 105

means of angle bars 102 and 103, the two halves of the web then passing in superposed relation to folder L.

What is claimed, is:

- 5 1. A multi-color offset perfecting press comprising: a plurality of groups of printing mechanisms, one group including a set of printing mechanism consisting of two units arranged to print on the same side of 45
- 10 the paper, each unit consisting of a form-carrying, a transfer and an impression member, the form-carrying and transfer members of each unit being arranged one above the other and the impression member out of 50
- 15 line with the other members to form an exposed operating side, said units facing the same way; another group of printing mechanisms including two sets of devices, one set including a unit consisting of a form- 55
- 20 carrying, a transfer and an impression member, the form-carrying and transfer members being arranged one above the other and the impression member out of line with the other members to form an exposed oper- 60
- 25 ating side, and the other set including a plurality of units, each consisting of a form-carrying member, a transfer member and an impression member, the form-carrying and transfer members of each unit being 65
- 30 arranged one above the other and the impression member out of line with the other members to form an exposed operating side, said units being grouped one above the other with their operating sides fac- 70
- 35 ing the same way, and the two sets of the second group being arranged back to back with the operating sides of the units outermost; said groups being arranged in spaced relation to provide an intervening gangway. 75
- 40 2. A multi-color offset perfecting press comprising: a plurality of groups of print-

ing mechanisms, one group including a set of printing mechanism consisting of two units arranged to print on the same side of the paper, each unit consisting of a form-carrying, a transfer and an impression cylinder; the form-carrying and transfer cylinders of each unit being arranged one above the other and the impression cylinder out of line with the other cylinders to form an exposed operating side, said units facing the same way; another group of printing mechanisms including two sets of devices, one set including a unit consisting of a form-carrying, a transfer and an impression cylinder, the form-carrying and transfer cylinders being arranged one above the other and the impression cylinder out of line with the other cylinders to form an exposed operating side, and the other set including a plurality of units, each consisting of a form-carrying cylinder, a transfer cylinder and an impression cylinder, the form-carrying and transfer cylinders of each unit being arranged one above the other and the impression cylinder out of line with the other cylinders to form an exposed operating side, said units being grouped one above the other with their operating sides facing the same way, and the two sets of the second group being arranged back to back with the operating sides of the units outermost, said groups being arranged in spaced relation to provide an intervening gangway.

Signed at Plainfield, in the county of Union and State of New Jersey, this 27th day of September, A. D. 1916.

DAVID JOHN SCOTT.
